UNITED STATES PATENT OFFICE

LUCY CHICHESTER ASHLEY, OF OKLAHOMA CITY, OKLAHOMA

AERIAL MAIL EXCHANGE

Application filed August 12, 1930. Serial No. 474,833.

This invention relates to aerial mail exchanges, and has particular reference to the provision of means whereby an aeroplane or other aircraft will be enabled to receive and deliver mail in pouches while in flight, thereby doing away with the necessity of making a landing for that purpose.

The present application is particularly directed to an improved mail pouch catching and delivering means carried by the aeroplane and of the type disclosed in U. S. Letters Patent No. 1,755,235, dated April 22, 1930.

The invention consists in the novel form, combination and arrangement of parts hereinafter more fully described, shown in the accompanying drawing and claimed.

In the drawing, wherein like reference characters indicate corresponding parts throughout the several views:

Figure 1 is a perspective view of an aerial mail exchange embodying my invention.

Figure 2 is an enlarged detail elevational view of the upper end of one of the masts; 25 and

Figure 3 is a longitudinal sectional view of the hook adapted to be suspended from the aeroplane for releasing and catching mail pouches.

Referring more in detail to the drawing, 30 5 indicates a circular supporting base upon which is mounted a circular turntable 6, rigid with and rising from opposite sides of which are a pair of hollow upright masts 7 having 35 signalling and illuminating lamps 8 upon their upper ends.

Slidably retained in undercut grooves 9 provided in the inner sides of the masts 7 and extending substantially from top to bottom of the latter, are plates 10 having wedge slots 11 therein which taper smaller in a downward direction, and attached to the upper ends of the slide plates 10 are cables 12 which pass upwardly over guide pulleys 13, journaled in the upper ends of the masts, and then pass downwardly through the latter and to a winding drum mounted as at 14, upon the turntable 6 adjacent one of the masts 7. The turntable 6 has crossed bars 15 fastened thereon for reinforcing purposes,

and the masts 7 are mounted upon the ends of one of these bars, which may be hollow as shown in Figure 3 of the aforesaid patent to permit the cable 12 to pass thereunder from one of the masts to the winding drum 55 mounted adjacent the other mast.

Mounted upon the ends of the other bar 15 at the edge of the turntable and intermediate the masts 7 are relatively short posts 16, and supported at its corners by the masts 7 and posts 16 at a suitable elevation above the turntable 6 is a net 17 for receiving pouches of mail, at at 18, released from the aeroplane 19, while in flight.

The mail pouch shown at 20 is suitably 65 attached to a flexible rope sling or loop 21, opposite portions of which are folded and wedged downwardly in the slots 11 of plates 10, whereby the mail pouch is suspended from the masts with the loop spread to present a horizontal upper strand that may be readily engaged by the catching hook suspended from the aeroplane as will later become apparent.

Suitably suspended from the aeroplane 19 75 by means of a cable 23 is a multiple-bill mail pouch releasing and catching hook preferably embodying a hollow shank 24 having a plurality of uniformly spaced bills 25 upon its lower end, with each of which is associated a spring-pressed normally operative pivoted keeper arm 26. The lower end portion of cable 23 enters the hollow shank 24 and encircling this end portion of the cable within shank 24 and between the upper end of the 80 shank and an abutment 27 provided on the lower end of cable 23, is a compression spring 28. It will thus be seen that, regardless of the position of the hook, a bill thereof will be properly presented to engage the loop 21, 90 and due to the elastic connection between the hook and the cable, the shock of suddenly taking on the load will be effectively cushioned. Any suitable means may be provided on the aeroplane to facilitate hoisting of the caught 95 mail pouch into the same.

In use, the cables 12 are unwound from the drum at 14 so as to lower the slide plates 10 to a point where an attendant may engage the folded portions of the loop 21 in 100

the wedge slots 11, whereupon, the cables are wound upon the drum to raise the slide plates and position the suspended mail pouch 20 at the required elevation. The turntable is then turned according to the direction of flight as governed by wind and other conditions so that the upper strand of loop 21 will be disposed in the path of the hook dropped from the aeroplane. Upon continued travel of the aeroplane after engagement of the hook with 10 the loop, the folded portions of the latter will be slightly lifted for complete release from the wedge slots 11 of plates 10, thereby insuring ready release of the load from the masts with little or no shock. The masts will 15 aid the pilot in selecting the proper path of travel to insure engagement of the hook with the loop, and by using the lamps 8, the pilot may be advised of the presence of mail to be caught and the location of the exchange 20 at night.

Each keeper arm 26 has a finger 30 at its pivoted end, which projects into the shank 24 to engage the under side of a head 31 on 25 the upper end of a plunger 32 which slidably projects through the lower end of shank 24 and has a notch 33 in one side of its lower end portion. The shank 24 has a tubular extension 34 on its lower end through which 30 the plunger 32 slidably projects, and provided in one side of the extension 34 is a notch 35 having a depending re-entrant portion 36. The plunger 32 is urged downwardly by a spring 37 to normally position the notch 33 below the entrance of notch 35 as shown in Figure 3. A spring 37 is mounted in shank 24 between the head 31 and a plug 38 secured in shank 24 below abutment 27, and above the plunger head 31. It will thus be seen that when a keeper 40 arm 26 strikes the rope 21 to take on the pouch 20, said arm will be swung to raise plunger 32 until the notch 33 registers with the entrance of notch 35, thereby allowing 45 the suspension ring 39 of pouch 18 to pass out of said notches and consequently release pouch 18 at a time when it will be directly above net 17 and not such a great distance therefrom as to permit of the pouch falling 50 clear of the net or falling with destructive force. Obviously, the ring 33 is suitably attached to the pouch 18 and initially engaged in the notches 33 and 35 while the latter are manually registered by moving the plunger 55 32 upwardly. Further, when the plunger 32 is allowed to lower, the ring 36 will be positively held in the notch 33 until a keeper arm 26 is depressed to raise the plunger 32 and again bring the notch 33 into registry with the entrance of notch 35. The re-entrant portion 36 of notch 35 permits the ring 39 and plunger 32 to lower when the ring 39 is engaged in the notches, and the extension 34 with the notch 35 forms what may be termed 60 a pouch-suspending hook. Likewise, the part 65

32 may be termed a pouch-releasing plunger in that it acts to substantially disengage the ring 39 from the element or hook 34.

What I claim as new is:

1. The combination with an aircraft, of a cable adapted to be lowered therefrom, and a catching hook having a shank attached to the lower end of the cable and provided with a plurality of equally spaced bills, each provided with a spring-pressed normally operative keeper element. 70
2. The combination with an aircraft, of a cable adapted to be lowered therefrom, and a catching hook having a shank attached to the lower end of the cable and provided with a plurality of equally spaced bills, each provided with a spring-pressed normally operative keeper element and an elastic connection between the cable and the shank of said hook. 80
3. The combination with an aircraft, of a cable adapted to be lowered therefrom, and a catching hook having a shank attached to the lower end of the cable and provided with an upper end member and a plurality of 90 equally spaced bills, each provided with a spring-pressed normally operative keeper element and an elastic connection between the cable and the shank of said hook embodying a spring encircling the cable within said shank, and an abutment on the lower end of the cable, said spring engaging an upper end member of the shank and said abutment. 95
4. The combination with an aircraft, of a cable adapted to be lowered therefrom, and a catching hook having a shank attached to the lower end of the cable and provided with a plurality of equally spaced bills, each provided with a spring-pressed normally operative keeper element, a pouch suspending and releasing means including a plunger carried by said catching hook, means to normally hold said plunger inoperative, and an operative connection between the keeper elements and said plunger for releasing the pouch when a keeper is swung to inoperative position. 100
5. A mail pouch delivering and catching device embodying a catching hook having a yieldable normally operative keeper element, a pouch-suspending hook carried by said catching hook, and means to automatically release a pouch from said pouch-suspending hook upon movement of the keeper element to inoperative position. 115
6. A mail pouch delivering and catching device embodying a catching hook having a yieldable normally operative keeper element, a pouch-suspending hook carried by said catching hook, and means to automatically release a pouch from said pouch-suspending hook upon movement of the keeper element to inoperative position, said last-named means embodying a plunger operatively connected to the keeper element and having a side notch, 120
- 125

said pouch-suspending hook embodying a tubular member having a side notch provided with a depending re-entrant portion, said plunger being slidable in said tubular member.

5 In testimony whereof I affix my signature.

LUCY CHICHESTER ASHLEY.
